COMPOSITE STRAND MATERIAL

William M. Camp, Glen Ridge, N. J., assignor to
The Clark Thread Company, Newark, N. J., a
corporation of New Jersey

Application May 27, 1942, Serial No. 444,731

2 Claims. (Cl. 57—140)

This invention relates to composite strand material adapted for use as thread cord and the like.

The problem to which the invention is primarily directed is the conversion of thread or cord made from abrasion-susceptible material into strand material resistant to abrasion and possessing generally properties enabling it to withstand successfully the demands and criteria of a successful sewing thread.

Yarn made of glass and certain organic synthetic fibers, e. g., those made from vinyl polymers, have valuable properties and numerous attempts have been made to manufacture thread cord and the like therefrom. They also possess, however, certain disadvantages which make it difficult to utilize such yarns in making sewing thread. The chief disadvantage is brittleness and susceptibility to abrasion.

Sewing thread is subject to very severe conditions in use. For example, it passes through the eye of the needle at a sharp angle and in frictional contact with the edges of the hole. It must therefore be highly flexible and resistant to abrasion. Threads made of glass yarn, for example, are, as such, not entirely satisfactory because of their susceptibility to abrasion and brittleness. In other words, their resistance to abrasion is very low and their brittleness very high.

The principle of the present invention will be illustrated by reference to the accompanying drawing, in which:

Fig. 1 shows a thread, cord or the like made from glass yarn;

Fig. 3 shows this cord provided with a wrapping of cotton silk or other abrasion resistance material;

Fig. 5 shows the wrapping coated and impregnated and bonded to the core by means of a film-forming adhesive;

Fig. 7 shows the product of Fig. 5 provided with a friction reducing coating;

Figs. 2, 4, 6, and 8 are transverse sections corresponding to Figs. 1, 3, 5, and 7, respectively; and

Fig. 9 is a longitudinal sectional view of the product illustrated in Fig. 7.

The core 1 is twisted from glass or other yarn so low in abrasion resistance as to be incapable of use per se as sewing material. This core is then provided with wrappings 2, e. g., of the diagonal type of strand material highly resistant to abrasion, e. g., cotton, silk, nylon. The

wrapped core is then subjected to a treatment to impregnate and coat the wrapping and bond it to the core by means of a film-forming adhesive 3. For this purpose, flexible film-forming adhesives in general may be used. It is necessary for the wrappings to be bonded properly to the core, otherwise they slip and pile up in one place on the core and cause failure in sewing. While, as stated, flexible film-forming adhesive in general may be used, those which are light colored and do not interfere with desired dyeing operations are preferred, e. g., latex, polyvinyl alcohol, hydrolyzed cellulose acetate, starch.

The coating, impregnation and bonding of the wrapping to the core may be accomplished by passing the wrapped core through a bath of the adhesive dissolved or dispersed in a suitable menstruum, aqueous or non-aqueous, depending on the nature of the adhesive. Those specifically above listed are dispensable in an aqueous medium.

Attempts to solve the problem by relying on such film-forming substances applied to the core without the wrapping provide some improvement but are not satisfactory to produce thread for sewing all types of fabrics. It is necessary to use both the wrapping and adhesive and to bond the former securely to the core in order to get sufficient abrasion resistance and strength to meet this necessary criteria.

Finally, in order to reduce friction, a friction-reducing finish coat 4 is preferably applied, e. g., a wax.

I claim:

35. 1. Composite strand material adapted for use as thread, cord and the like comprising a core of twisted glass yarn; a wrapping of abrasion-resistant strand material covering said core; said wrapping being impregnated and coated and bonded to the core with a film-forming adhesive, and a friction-reducing coating on the surface of said coated and impregnated wrapping.

40. 2. Composite strand material adapted for use as thread, cord and the like comprising a core of twisted yarn susceptible to abrasion when used in sewing; a wrapping of abrasion-resistant strand material covering said core; said wrapping being impregnated and coated and bonded to the core with a film-forming adhesive, and a friction-reducing coating on the surface of said coated and impregnated wrapping.
